(57) **CLAIM**

The ornamental design for a radiographic detector protector, as shown and described.

DESCRIPTION

FIG. 1 is a top rear perspective view of a radiographic detector protector having a radiographic detector panel held within the radiographic detector protector.

FIG. 2 is a top rear perspective view of a radiographic detector protector without a radiographic detector panel held within the radiographic detector protector.

FIG. 3 is a bottom front perspective view thereof.

FIG. 4 is a top front perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.

The large unshaded surfaces shown in FIG. 1 and the broken lines shown throughout the views represent the portions of the design that form no part of the claim.
